RICHARD C. SHIPLEY AND JAMES R. QUIGG, OF KANSAS CITY, MISSOURI.

AXLE-BOX-WEDGE MECHANISM.

Application filed October 27, 1926. Serial No. 144,491.

Our invention relates to improvements in axle box wedge mechanisms. It is particularly well adapted for use in connection with the wedges used for holding the driving axle boxes of locomotives.

One of the objects of our invention is to provide a novel wedge mechanism of the kind described, which is simple, cheap, strong, durable, not liable to get out of order, which will automatically keep the wedge tight between the box and frame, which is so disposed as to afford a firm rigid support for the usual wedge, which is also disposed so as to be wholly above the binder plate, thereby eliminating liability of striking objects and being injured thereby, and which is readily adapted to be applied to axle box mechanisms now in use.

The novel features of our invention are hereinafter fully described and claimed.

In the accompanying drawings, which illustrate my invention,

Fig. 1 is a side elevation of my improved axle box mechanism, shown applied to the axle box structure of a locomotive.

Fig. 2 is a section on the line 2—2 of Fig. 1.

Fig. 3 is a section on the line 3—3 of Fig. 4.

Fig. 4 is a vertical sectional view through a portion of the frame and axle box.

Fig. 5 is a perspective of my improved lower wedge.

Fig. 6 is a perspective of a portion of the binder plate.

Fig. 7 is a perspective of the lower portion of the upper wedge.

Fig. 8 is a horizontal sectional view showing a modified form of the spring mechanism.

Fig. 9 is a vertical section through the lower part of the upper wedge.

Similar reference characters designate similar parts in the different views.

1 designates the body of the frame, having the pedestal 2 and the binder plate 3. 4 designates the usual axle box mounted in the frame, and 5 the usual type of wedge upwardly movable between the pedestal 2 and the box 4 over the binder plate 3, so as to tighten between the frame and box for firmly holding the box.

In order to always keep the wedge 5 in a tightened wedging position, we provide 55 a member comprising a lower wedge 6, Fig. 5, the upper portion of which is T-

shaped and is slidably fitted in a similarly shaped inclined groove 7 in the lower end of the upper wedge 5, Figs. 7 and 9.

The wedge 6 in its lower portion is of an inverted T shape in cross section, which portion is slidably fitted in a similarly shaped horizontal groove 8, disposed in the upper side of the binder plate 3 transversely to the length thereof and in the same vertical plane as the groove 7. The wedge 6 has two intermediate longitudinal wedge shaped portions at opposite sides thereof respectively, designated by 9 and having inclined upper sides 10 which engage the lower end of the upper wedge 5.

When the wedge 6 is moved in the grooves 7 and 8 in one direction, the upper wedge 5 will be lifted thereby so as to tightly engage the box 4 and pedestal 2, thus compensating for wear of the parts. In order that such movement in said direction shall be effected automatically, we provide mechanism including a spring, which mechanism, in the preferred form shown in Figs. 1, 2 and 3, the spring consists of two partially elliptical resilient plates 11 lying one on the other and mounted on the outer ends of two collars 12 and 13 respectively bearing against the binder plate 3 and the pedestal 2.

The ends of the spring plates 11 are respectively provided with notches 14 through which respectively extends bolts 15, which extend respectively through the collars 12 and 13, and are fitted in threaded holes provided in the binder plate 3 and the pedestal 2.

The lower wedge 6 has a central stem 16 which extends horizontally through and is slideable in central holes provided therefor in the plates 11. The stem 16 is threaded and has fitted on it a nut 17 which bears against the outer spring plate 11. The tension of the plates 11 is such that the plates always exert a pressure tending to draw the wedge 6 inwardly in the grooves 7 and 8, thereby lifting the wedge 5 until the latter is tightened between the box 4 and pedestal 2. A lock nut 18 on the stem 7 bears against the nut 17.

By having the wedge 6 mounted so as to move horizontally transversely to the length of the binder plate 3, the lower wedge 6 provides a rigid support for the upper wedge 5, and the spring mechanism can be disposed wholly above the lower side of the binder plate 3, so that such mechanism is

not liable to be struck and injured by objects along the right of way. The disposition of the wedge 6 transversely to the length of the binder plate 3, also permits of the use 5 of the usual binder plate 3 and box wedge 5 with the latter located wholly above the binder plate.

By adjusting the nuts 17 and 18, the 10 spring plates 11 may be given desired tension. As the box 4, pedestal 2 or wedge 5 wears, the spring plates 11 will draw the wedge 6 so as to raise the wedge 5 to compensate for the wear and to hold the wedge 5 tightly against the box and pedestal.

15 The device may be adapted to structures now in use by providing the grooves 7 and 8 in the wedge 5 and binder plate 3, and by providing threaded holes in the binder plate 3 and pedestal 2 for the bolts 15, and mounting 20 the parts in the manner described.

In the form of our invention shown in Fig. 8, the parts are as already described, with the exception that in lieu of the spring plates 11, a coil spring 20 encircles the stem 16 and bears at one end against a collar 19, which bears against the nut 17, the other end of the spring 20 bearing against a collar 21 on the stem 16 and bearing against a bracket 22 held by the bolts 15 against the binder 25 plate 3 and the pedestal 2. The spring 20 operates in the manner of the spring plates 11 to draw the lower wedge 6 so as to lift the wedge 5.

We do not limit our invention to the structures shown and described, as many modifications, within the scope of the appended 35 claims, may be made without departing from the spirit of our invention.

What we claim is:—

40 1. In an axle box wedge mechanism, the combination with a frame, an axle box thereon, and a vertically movable wedge engaging the frame and box, of a second wedge horizontally movable on the frame transversely to the length of the frame and engaging the first named wedge and arranged, when moved in one direction, to move the first named wedge to tighten the latter between the box and frame.

45 2. In an axle box wedge mechanism, the combination with a frame having a horizontal groove transverse of the length of the frame, an axle box on said frame, and a vertically movable wedge engaging said frame and box, of a second wedge longitudinally reciprocative in said groove, and having an inclined upper side engaging the lower end of the first named wedge.

50 3. In an axle box wedge mechanism, the

combination with a frame having a horizontal groove transverse of the length of the frame, an axle box on said frame, and a vertically movable wedge engaging said frame and box and arranged, when moved upwardly to tighten between the box and frame, of a second wedge longitudinally reciprocative in said groove and having an inclined upper side directly engaging the lower end of said first named wedge, and means including a spring for normally automatically forcing the second wedge in said groove in a direction such that the second wedge will lift the first named wedge.

4. In an axle box wedge mechanism, the combination with a frame comprising a body and a binder plate fastened to the body, an axle box on said frame, and a vertically movable wedge engaging the body and box above said binder plate, of a second wedge horizontally movable on said binder plate transversely of the length thereof and having an inclined upper side engaging the lower end of the first named wedge and arranged, when moved in one direction, to lift the first named wedge to tighten the latter between the body and box.

5. In an axle box wedge mechanism of the kind described, the combination with a frame having a horizontal groove transverse of the length of the frame, an axle box on 90 said frame, and a wedge engaging the box and frame and vertically movable between the frame and box, and when moved upwardly serving to tighten between the box and frame and having a transverse inclined 95 groove parallel with the first named groove, of a second wedge slidable in said groove, and means for sliding the second wedge to lift the first named wedge.

6. In an axle box wedge mechanism, the 100 combination with a frame having a binder plate provided in its upper side with a horizontal groove transverse to the length of the binder plate, an axle box on said frame, and a wedge upwardly movable between said 105 box and frame above said binder plate and engaging said box and frame and having in it an inclined groove parallel with the first named groove, of a second wedge slidable fitted in said groove for lifting the first 110 named wedge when the second wedge is moved in one direction, and means including a spring for sliding the second wedge in said direction.

In testimony whereof we have signed our 115 names to this specification.

RICHARD C. SHIPLEY.
JAMES R. QUIGG.
